APPARATUS FOR PRESHRINKING CLOTH

Henry A. Woodhead, Graniteville, S. C.

Application November 24, 1934, Serial No. 754,577

10 Claims. (Cl. 26—19)

This invention relates to apparatus for pre-shrinking cloth for the purpose of substantially eliminating shrinkage in both weft and warp in subsequent laundering operations.

5 I have found that the shrinkage resulting from laundering operations is not due solely to increased crinkle which may be induced in the warp or weft yarns but that it is also due to the physical rearrangement and readjustment of the 10 yarns and fibers due to the mechanical working and reconditioning and flexing of the fabric in all directions while in its plastic condition during laundering. I obtain this rearrangement of the warp and weft yarns by mechanically working the web rapidly and positively. My process for 15 pre-shrinking is preferably carried out after the usual preliminary steps, such as singeing, removing the warp sizing, bleaching, dyeing, printing, mercerizing, drying calendering and polishing, or other customary operations have been performed upon the web so that no subsequent operation is necessary which might impair the full 20 advantages of the pre-shrunk condition attained.

In my co-pending application Serial No. 25 674,495, filed June 6, 1933, now Patent No. 1,982,720, dated December 4, 1934, I have disclosed processes and apparatus for mechanically working a fabric web to readjust the positions of the component yarns of the web within the body 30 thereof in order to impose a pre-shrunk condition on the web. The present invention is similar in its more general aspects to that disclosed in said application, inasmuch as herein also the pre-shrunk condition is imposed upon the web 35 by mechanically working within the body of the web. In carrying out the present invention a plurality of resilient fingers are provided which mechanically work the web as it passes over a roll that forms a working surface for the fingers.

40 The fingers are caused to penetrate the web, or at least firmly grip the latter, for compressing the web warp-wise by effecting readjustment of the positions of the yarn components of the web within the body thereof.

45 In the drawing:

Figure 1 is a side elevational view in simplified diagrammatic form of apparatus embodying the present invention;

Figure 2 is a fragmentary plan view on an enlarged scale of a portion of the apparatus illustrated in Figure 1; and

Figure 3 is an enlarged perspective view of the end portion of one of the resilient fingers that mechanically work the web.

55 I preferably carry out my pre-shrinking oper-

ations as part of the finishing operation upon a fabric and in Figure 1 the dotted line 10 represents the center line of a fabric web which it is assumed has previously been subjected to processing operations such as bleaching, dyeing, 5 printing, calendering, etc., or combinations thereof. The web 10 is drawn from a bin or truck 1 over guide rolls 2 by a pair of feed rolls 3, 4.

Although I have successfully carried out my 10 pre-shrinking operation while the fabric is in a dry condition, I prefer to have it in a plastic condition. While the fabric may be processed in a wet condition resulting from some preliminary operation, I have illustrated my pre-shrinking 15 operations as commencing by passage of the fabric over a steam chest 5 where the fabric is moistened and rendered plastic. If desired the fabric may be rendered plastic by passing it through a mangle in which a final sizing is im- 20 parted to the web. The plasticizing of the web permits it to be more easily adaptable to the mechanical working which I impose upon it for effecting a rearrangement of the component 25 yarns and fibres to thus attain a pre-shrunk 30 condition in which the yarns are in a state of substantial equilibrium.

The feed roll 4 is positively driven as by a chain 6 operated, for example, from the variable speed shaft 7 of a "Reeves variator" 8. The web 35 is taken up on delivery from rolls 3, 4 by a pair of rolls 11, 12 the latter of which is also positively driven, as by a chain 13 operated from the constant speed shaft 14 of variator 8. Rolls 11, 12 are driven at a slightly slower rate than feed 40 rolls 3, 4 for a purpose which will be apparent later.

The roll 12 constitutes a working surface against which the ends of a plurality of spaced resilient fingers 15 operate for imposing a pre- 45 shrunk condition on the web. The free end portions of fingers 15 are bent at an angle to their shanks 16 by means of which they are supported in a clamp bar 17 extending parallel to roll 12. The clamp 17 bar is supported for vertical and horizontal adjustment so that the free ends of fingers 15 may be adjusted vertically and horizontally with respect to the nip between the rolls 11 and 12. Clamp bar 17 is also rotatably adjustable to regulate the pressure with which fingers 15 bear against the roll 12 and web thereon. The detailed construction of clamp bar 17 and the manner in which it is adjustably mounted are described in my co-pending application Serial 50 No. 754,575, filed, November 24, 1934. Briefly, the 55

adjusting arrangement consists of discs 18 that support the bar 17 at each end and which are rotatably adjustable on slides 20. The slides 20 are horizontally adjustable toward and away from roll 12 on blocks 21 which in turn are vertically adjustable on side members 22 of the machine frame.

The shanks 16 of the fingers 15 extend between spacers 24 located intermediate a series of irregularly shaped flat-sided cams 25 on a cam shaft 26 also mounted parallel to roll 12. The cams 20, one of which is provided for each finger, are adapted to act on the shanks 16 of the fingers 15 for rapidly moving their end portions over the surface of roll 12 to grip the web and force it toward the nip between the latter and roll 11. The resilience of the fingers 15 causes their retraction from engagement with the web.

As shown in Figure 3, the undersides of the end portions of fingers 15 are channelled or otherwise formed to provide two points 27 on each finger for penetrating the surface of the web and firmly gripping the latter. The end portions of the fingers that are located between the points 27 act to limit the extent to which the points penetrate the web. The ends of the fingers are also chamfered or cut back at 28 so that the points 27 may readily penetrate the surface of the web and be withdrawn from the latter without tearing or otherwise injuring the web.

Cam shaft 26 is operated from drive 7 by a chain 29. The cams operate against the shanks 16 to cause the fingers 15 to grip the web and force it forwardly toward the nip between rolls 11 and 12 at a slightly faster rate than the web is advanced by these rolls. The fingers 15 are operated at a rate with respect to feed rolls 3, 4 that prevents the undue accumulation of slack in the web while at the same time permitting the web to be forced forward by the fingers into the confined zone formed by the nip between rolls 11, 12 without imposing warp-wise tension on the web due to its forward movement.

As shown in Figure 2, the series of cams 25 on cam shaft 26 form several groups of evenly spaced cams 25a, 25b, and 25c, arranged so that the groups operate in rapid succession for continuously engaging fingers with the web. Each group consists of a plurality of cams as 25a, etc., acting in unison on related evenly spaced fingers 15a, etc., so that the web is always gripped by the points 27 of a number of fingers 15 spaced evenly across the width thereof in order that it may be advanced evenly.

Due to the operation of rolls 11, 12 at a slightly slower rate than feed rolls 3, 4 the web 10 is free from warp-wise tension as it is shoved and pushed forwardly into the rolls 11, 12. Upon being engaged with the web by the cams 25 the points 27 of the fingers 15 are forced into and between the fibres of both the weft and warp yarns of the web. The points 27 of the fingers 15 are so small that they tend to operate not only upon the individual weft yarns but also actually into and between the fibres making up the warp yarns. The points 27 are forced into the web at a slight angle to its surface due to the direction of movement of the fingers 15 and the curvature of the web in passing over the roll 13.

Thus, on penetrating, or at least firmly gripping, the web while it is free from tension the fingers 15 tend to loosen the component yarns of the web and exert a shoving action that positions the weft yarns more closely together and acts longitudinally of the warp yarns to shove

them together into a fatter or thicker state, i. e. with increased diameters.

As mentioned above, the fingers 15 are operated by the cams 25 to force the web toward the nip between rolls 11, 12 at a faster rate than these 5 rolls act to take up the web from feed rolls 3, 4 and advance it. Consequently, the forward movements of fingers 15 on the surface of roll 12 cause a shoving together of the fibres of the warp yarns as well as a compacting action on the weft 10 yarns that are gripped by the points of the fingers. As a result, there is a mechanical readjustment and repositioning of the component yarns of the web, as distinguished from a mere crinkling of the yarns. Thus, a pre-shrunk condition is imposed 15 on the web by actually compressing and contracting it warp-wise.

The surfaces of rolls 11 and 12 may be heated in any suitable manner so that the web is set and dried in its pre-shrunk condition as it passes 20 between these rolls. Additional drying cans may, of course, be used. The web is delivered by rolls 11, 12 onto a platform 30 that supports the web to prevent the imposition of warp-wise tension thereon, due to sagging, that might diminish the 25 pre-shrinking effect attained by fingers 15. The web is taken up from platform 30 by an endless band 31 and carried forwardly to folding apparatus 32 that folds the finished fabric in piles in a bin or truck 33. The carrier band 31 is operated to 30 take up and advance the web at its rate of delivery from rolls 11, 12 in order to avoid imposing warp-wise tension on the web that might act to diminish the pre-shrunk effect attained.

The web on passing between the feed rolls, 3, 4, 35 after being plasticized, may be found to have the width desired in the finished pre-shrunk fabric. In this event the web may be delivered directly from feed rolls 3, 4 to the rolls 11, 12 for working by the fingers 15 to compress it warp-wise. 40 If, however, the web is found to have a greater width than desired it may be reduced weft-wise by passing it through a tentering frame, or other suitable device, as disclosed in the above mentioned application. In such case the tentering 45 frame would take up the web from rolls 3, 4, stretch it weft-wise to the desired width and deliver it to rolls 11, 12 for working by the fingers 15.

Although an illustrative embodiment of my 50 invention has been shown and described in detail, there are many changes and variations that may be made without departing from the invention and, therefore, I desire and intend to include all such changes and variations within the scope 55 of the appended claims.

I claim:

1. In apparatus for mechanically working a fabric web to impose a pre-shrunk condition thereon; a plurality of spaced, reciprocable fingers adapted to grip the web at points spaced transversely thereof; and means for reciprocating said fingers for causing them to grip the web and exert loosening, pulling and shoving actions on the component yarns thereof for readjusting their positions within the body of the web to effect a warp-wise compression thereof.

2. In apparatus for mechanically working a fabric web to impose a pre-shrunk condition thereon; web-carrying means; a plurality of 70 spaced, reciprocable web-working fingers having end portions adapted to grip the web at a plurality of points spaced transversely thereof; and means for reciprocating said fingers to grip the web as it is advanced by said carrying means 75

and force it forwardly at a faster rate than it is advanced by said carrying means for causing said fingers to readjust the positions of the component yarns of the web and effect a warp-wise compression thereof.

5 3. In apparatus for mechanically working a fabric web to impose a pre-shrunk condition thereon; a web-supporting surface; a plurality of evenly spaced, reciprocable web-working fingers adapted to grip the web and advance it on said surface; and means for reciprocating said fingers in unison to cause them to grip the web at a plurality of points spaced evenly across the width thereof for advancing the web evenly over

10 15 said surface.

15 4. In apparatus for mechanically working a fabric web to impose a pre-shrunk condition thereon; a web-supporting surface; a plurality of spaced web-working fingers adapted to grip 20 the web and advance it on said surface; and means for rapidly and successively operating independent groups of said fingers, each group comprising a number of fingers, for continuously gripping and advancing the web.

20 25 5. In an apparatus for mechanically working a fabric web to impose a pre-shrunk condition thereon; a web-supporting surface; a plurality of web-working fingers supported in spaced relation adjacent said surface and operable to grip the web and move it on said surface; and means for operating independent groups of said fingers in rapid succession, each group comprising a number of evenly spaced fingers gripping the web simultaneously, whereby the web is continuously and evenly advanced on said surface by fingers gripping the latter at points spaced evenly across the width thereof.

25 30 6. In apparatus for mechanically working a fabric web to impose a pre-shrunk condition thereon; web-supporting means; means for driving said supporting means to advance the web; a plurality of spaced fingers mounted adjacent said web-supporting means adapted to be moved into gripping engagement with the web as it is advanced by said supporting means; cam means for engaging said fingers with the web and moving them forwardly with respect to said web supporting and advancing means; and means for operating said cam means to move said web-

35 40 gripping fingers forwardly with respect to said supporting means at a faster rate than the latter advances the web for causing said fingers to exert shoving actions on the component yarns of the web to compress the latter warp-wise.

40 45 5. 7. In apparatus for mechanically working a fabric web to impose a pre-shrunk condition thereon; web-supporting means; means for driving said supporting means to advance the web; a plurality of spaced, resilient fingers mounted adjacent said web-supporting means adapted to be moved into gripping engagement with the web as it is advanced by said supporting means; and cam means periodically acting on said fingers for engaging them with the web and moving them

forwardly with respect to said web supporting and advancing means at a faster rate than the latter advances the web for causing said fingers to exert shoving actions on the component yarns of the web to compress the latter warp-wise, the 5 resiliency of said fingers acting to retract them from gripping engagement with the web when said cams are ineffective to move them forwardly with respect to said web-supporting means.

8. In apparatus for mechanically working a fabric web to impose a pre-shrunk condition thereon; web-feeding means; web-carrying means for taking up the web from said feeding means and advancing it; driving means for said feeding means; means for driving said carrying means at 10 a slower rate than said feeding means to relieve the web of warp-wise tension as it is taken up by said carrying means; a plurality of spaced web-working fingers adapted to grip the web on said carrying means; and means for operating said 15 fingers to cause them to grip the web and force it forwardly on said carrying means at a faster rate than it is advanced by the latter, whereby said fingers exert shoving actions on the web, while it is relieved of warp-wise tension, to readjust the 20 25 positions of the component yarns of the web for compressing it warp-wise.

9. In apparatus for mechanically working a fabric web to impose a pre-shrunk condition thereon; web-feeding means; web-carrying means 30 for taking up the web from said feeding means and advancing it; driving means for said feeding means; means for driving said carrying means at a slower rate than said feeding means to relieve the web of warp-wise tension as it is taken up by 35 said carrying means; a plurality of spaced web-working fingers adapted to grip the web on said carrying means; and means for operating said fingers to cause them to grip the web and force it forwardly on said carrying means at a faster 40 rate than it is advanced by the latter, whereby said fingers act to prevent the accumulation of slack in the web between said feeding and carrying means and exert shoving actions on the component yarns of the web to readjust their positions 45 within the body of the web to effect a warp-wise compression of the latter.

10. In apparatus for mechanically working a fabric to impose a pre-shrunk condition thereon; a pair of rolls for engaging and advancing the 50 web; means for driving said rolls; a plurality of spaced fingers supported adjacent said rolls adapted to grip the web and press the latter against the surface of one of said rolls; and means for engaging said fingers with the web and 55 moving them forwardly over the surface of said roll at a rate to force the web toward the nip between said rolls faster than it is advanced by said rolls for causing said fingers to exert shoving actions on the component yarns of the web to 60 readjust their positions within the body of the web and effect warp-wise compression thereof.

HENRY A. WOODHEAD.
